SCREW DRIVER CONDITIONER

George E. Brulport, Rossmoyne, Ohio

Application August 1, 1947, Serial No. 765,355

6 Claims. (Cl. 51—214)

1

This invention relates to a screw driver reconditioning device.

It is an object of this invention to provide a means for reconditioning screw drivers for watch repair work and the like, for sharpening the blade of the screw driver, and providing the proper width of bit on the blade.

Another object of this invention is to provide a sharpening device of the kind to be more particularly described hereinafter, having a pair of abrasive rollers between which the screw driver blade or the like is adapted to be engaged for cutting the proper bit on the blade, the rollers being supported for adjustment relative to each other so that various sized screw drivers may be accommodated.

Another object of this invention is to provide a device of this kind having transversely spaced apart abrasive rollers pivotally connected together by their supporting means and means for adjusting the spaced apart relation of the abrasive rollers.

A further object of this invention is to provide an indicating means carried by the abrasive roller supports for indicating the spaced apart relation of the rollers.

With the above and other objects in view, my invention consists in the arrangement, combination and details of construction disclosed in the drawings and specification, and then more particularly pointed out in the appended claims.

In the drawings:

Figure 1 is a side elevation of a screw driver reconditioning device constructed according to an embodiment of this invention;

Figure 2 is a front elevation;

Figure 3 is a fragmentary transverse section partly broken away taken on the line 3—3 of Figure 2; and

Figure 4 is a bottom plan view partly broken away and partly in section.

Referring to the drawings, the numeral 10 designates generally a screw driver of the type generally used in watch repair work and the like on which a properly shaped screw engaging blade 11 is secured. For sharpening the blade 11, I have provided a pair of spaced apart abrasive members or rollers 12 and 14 between which the blade 11 is adapted to be engaged for reconditioning the edge thereof.

The rollers 12 and 14 are supported on the support 15 by pivotally connected supporting links 16 and 17 at each end thereof. The support 15 is formed of a pair of intersecting crossed supporting links 16 and 17 hingedly connected to

2

gether intermediate their lengths by hinge pins or bolts 18.

A pair of supporting members 19 and 20 are disposed at each end of the rollers 12 and 14. 5 A bolt 19 engages through one of the abrasive members as 12 and between the upper end of the supporting links 17 at each end. The supporting links 16 are connected at their upper ends to the bolt 19 engaging through the abrasive roller 14.

The lower end of the links 16 and 17 is free and pivotal movement of the links about their central pivot point 18 will move the abrasive rollers 12 and 14 farther apart or closer together to determine the size of point on the blade 11.

The ends opposite the rollers of the supporting links 16 are connected together by a rod 21 disposed in parallel relationship to the abrasive roller 14. The rod 21 is secured on the link 16 by

15 rivet heads 22 or other suitable fastening device. A similar rod 24 is connected between the lower ends of the other supporting links 17 and connected by similar rivet heads 25 or other suitable fastening device.

20 25 An adjusting bolt 26 is rotatably secured between the rods 21 and 24 midway the length thereof below the rollers 12 and 14 and below the hinge points 18 thereof. The adjusting screw 26 loosely engages through one of the rods as 21 and threadably engages in the other rod 24 as indicated in the Figure 4.

25 30 A rod 27 is disposed about the bolt 26 outwardly of the sleeve 21 and a knurled finger grip 28 is provided on the screw 26 outwardly of the sleeve 27. One of the supporting links as 16 is provided with a series of indicating marks as 29 below the pivot point 18.

35 40 A pointed indicator as 30 is fixed to or carried by the adjacent link as 17 and cooperates with the indicia 29 for indicating the space between the rollers 12 and 14. This space between the rollers will be proportional to the width of the edge of the blade 11 on the screw driver 10.

45 50 In the use and operation of this screw driver reconditioning device the distance between the abrasive members 12 and 14 is initially adjusted by turning the adjusting screw 26 until the pointer 30 registers with the selected index mark 29. At this time the space between the rollers will be indicated at this point.

55 The blade of the screw driver 10 is then moved longitudinally of the rollers 12 and 14 for cutting the blade to the desired contour with the necessary selected edge thereof.

I do not mean to confine myself to the exact

details of construction herein disclosed but claim all variations falling within the purview of the appended claims.

Having thus described my invention, what I claim is:

1. A screw driver sharpener comprising a pair of transversely spaced apart cylindrical abrasive members, supporting means for said abrasive members, means carried by said supporting means for selectively adjusting the distance between said abrasive members, and means carried by said supporting means indicating the spaced apart relation of said abrasive members.

2. A screw driver reconditioner comprising a pair of transversely spaced apart cylindrical abrasive members, a pair of pivotally connected supporting members at each end of said abrasive members, means securing each of said abrasive members at each end of one of said supporting members, and an adjusting screw carried by said supporting members securing said supporting members in selected pivoted position for adjusting the spaced apart relation of said abrasive members.

3. A sharpening device comprising a pair of spaced apart abrasive members, a pair of supporting members for each of said abrasive members, means pivotally connecting the supporting members of one of said abrasive members to the supporting members of the other abrasive member and adjusting screw engaging between the supporting members of one of said abrasive members and the supporting members of the other abrasive member for selectively adjusting the spaced apart relation of said abrasive members.

4. A sharpening device comprising a pair of

transversely spaced apart elongated abrasive members, a supporting link at each end of said abrasive members, means pivotally connecting the supporting links of one abrasive member to the

5 supporting links of the other member intermediate the length thereof in crossed relation, and adjusting means engaging between said crossed links opposite the pivot thereof for adjusting the spaced apart relation of said abrasive members.

10 5. A sharpening device comprising a pair of transversely spaced apart elongated abrasive members, a supporting link at each end of said abrasive members, means pivotally connecting the supporting links of one of said members to the supporting links of the other of said members in crossed relation, adjusting means engaging between said crossed links opposite the pivot thereof for adjusting the spaced apart relation of said abrasive members, and correlated means 15 carried by at least one pair of crossed links indicating the spaced apart relation of said abrasive members.

20 6. A sharpening device comprising a pair of transversely spaced apart elongated abrasive members, a supporting link at each end of said abrasive member, means pivotally connecting the supporting links of one of said abrasive members to the supporting links of the other abrasive member, an adjusting screw engaging between said 25 pivotally connected links for adjusting the spaced apart relation of said abrasive member, an index on one of said links, and a pointer of another of said links for registering with said index for indicating the spaced apart relation of said abrasive members.

GEORGE E. BRULPORT.
